PHONOGRAPH RECORD REPEATER

Robert A. Wolfe, Fairfield, Conn., assignor to Spear Products, Incorporated, Bridgeport, Conn., a corporation of Connecticut

Application April 11, 1958, Serial No. 50,443

Term of patent 14 years

(Cl. D56—4)

Fig. 1 is a plan view of a phonograph record repeater showing my new design:

Fig. 2 is an edge view thereof looking from the right of Fig. 1;

Fig. 3 is a section substantially on the plane of line 3—3 of Fig. 1; and

Fig. 4 is a section substantially on the plane of line 4—4 of Fig. 1.

I claim:

The ornamental design for a phonograph record repeater, substantially as shown.
